pany, Cincinnati, Ohio, a corporation of Ohio

Application November 22, 1933, Serial No. 699,291

4 Claims. (Cl. 49—84)

This invention relates in general to a process for bending glass and in particular to a process for producing corner or angle tiles and has for its principal object the provision of a novel and highly efficient process adapted to be practised at a minimum of expense and of time.

In the drawing illustrating the invention, Fig. 1 is a side elevational view of a mold having a glass tile positioned therein and having associated therewith a suitable heat applying device which is shown only in part.

Fig. 2 is a view taken on line 2—2 of Fig. 1.

The present invention is adapted to be practised by use of a mold 5 which has a base 6, sides 15 7 and inturned top flanges 8 extending longitudinally of the sides. The ends of the mold are open. Extending longitudinally of the base 6 is a vertical support 9 and the top edge of which is disposed in a plane below but adjacent to the end faces of the flanges 8. A pair of stop members 10 and 11 are associated with the interior face of the base 6 in spaced relationship with the support 9. These supports may be adjustable to greater heights and to different angles than those shown or they may be made removable and replaceable by other stop members of different sizes.

A flat glass tile 12 is slipped into position between the under faces of the flanges 8 and the top edge of the support 9, assuming the substantially balanced position shown clearly in Fig. 1. It will be noted that the tile is of somewhat less width than the distance between the sides 7 of the mold in order to allow for expansion of the glass under heat.

In bending the flat glass tile 12 to the angular form shown in Fig. 1, heat is applied to the median line 20 of the tile as defined by the top edge of the support 9. This application of heat may be effected in a suitable manner. For the purpose of illustration there is herein shown a burner 13 having a restricted elongated jet 14 which is placed directly above and along the portion of the tile at which the bend is to be effected as seen in Fig. 1. The burner is mounted adjustably on a vertical support 15 and may have associated therewith the air header 16 and the gas header 17 which are connected with the burner by suitable conduits 18 and valves 19 such as shown (Fig. 1).

The heat is applied along the median line as described until the portion of the tile along said line is brought to a bendable condition. At this time the lateral portions of the tile adjacent said median line 20 bend down of their own weight

into predetermined positions below the plane of the median portion, the stop members 10 and 11 limiting this bending movement of said lateral portions. It is obvious that the adjustment of the stop members or replacement thereof by members of different size, is resorted to for effecting a similar change in the angular relation of the down bent portions of the tile.

The median line portion of the tile 12 is heated to approximately 1500° F. which is approximately 10 the temperature at which glass attains a bendable state. The lateral portions of the tile bordering the intermediate highly heated portion remain relatively cool and consequently each of said lateral portions remains of itself unbent. 15 The tile after cooling retains permanently the angular shape given it in the process just described.

It should be pointed out, that according to the present invention, the heat is applied to the glass 20 plate on the upper surface and it is the upper surface which must make the greater bend or arc since the lateral portions of the plate are carried downwardly of their own weight. In other words, the outside arc of the bend in the plate is 25 necessarily greater than the inside arc which contacts the upper edge of the support 9. Thus any danger of breakage of the glass which might occur if the heat were applied to the under side of the glass plate, is effectively obviated. 30

What is claimed is:

1. The method of forming a glass or similar corner tile and comprising placing a flat tile on a support contacting the tile along an intermediate portion only, applying heat to the opposite 35 surface of the tile and along said intermediate supported portion only, and continuing the application of heat until said intermediate portion is in bendable state and the relatively cool portions of the tile on both sides of said intermediate 40 portion bend down of their own weight into angular relationship with one another in predetermined positions below the plane of said intermediate portion.

2. The method of simultaneously bending two 45 sections of a glass or similar plate in one operation to form a corner tile, the method comprising placing the unbent plate on a support which contacts the plate only along an intermediate area on the under surface of the plate leaving clear the 50 space beneath the lateral sections of the plate, and applying heat to the upper surface of the plate in the portions thereof opposite said contacted area of the under surface to render said portions bendable for causing said lateral sec- 55

tions of the plate to bend downwardly of their own weight into the clear spaces therebeneath.

3. The method of simultaneously bending two sections of a glass or similar plate in one operation to form a corner tile, the method comprising placing the unbent plate on a support which contacts the plate only along an intermediate line on the under surface of the plate, applying a flame to the upper surface of the plate along a line opposite said under surface contact line to render bendable the area of the plate along said lines for causing said lateral sections of the plate to bend downwardly of their own weight, and limiting the downward bending of said sections

when the latter have attained predetermined angles of relationship with one another.

4. The method of bending a glass plate, comprising placing the unbent plate on a support which contacts the plate only along an intermediate area on the under surface of the plate leaving clear the space beneath the lateral sections of the plate, and applying heat to the upper surface of the plate along the portions thereof opposite said contacted area of the under surface to render said portions bendable for causing the lateral sections of the plate to bend downwardly of their own weight into the clear spaces therebeneath.
